UNITED STATES PATENT OFFICE.

DANIEL HOPKINS, OF CASCADE, NEW HAMPSHIRE.

TRAIN-STOP.

1,144,902.

Specification of Letters Patent. Patented June 29, 1915.

Application filed August 4, 1913. Serial No. 782,965.

To all whom it may concern:

Be it known that I, DANIEL HOPKINS, a citizen of the United States, residing at Cascade, in the county of Coos and State of New Hampshire, have invented certain new and useful Improvements in Train-Stops; and I do hereby declare the following to be a full, clear, and exact description of the invention, such as will enable others skilled in the art to which it appertains to make and use the same.

This invention relates to new and useful improvements in automatic train stops and has for its object the provision of a device by means of which a train running at a high rate of speed may be easily and quickly brought to a stop through automatic means and without in any way necessitating the use of manual labor in performing the above mentioned operation.

Another object of my invention is the provision of a train stop which will operate in connection with the block signaling system of the railroad and thereby eliminate any accidents and great loss of life and property through such accidents.

Still another object of my invention is the provision of a device of the above character wherein the shutting off of the power and the applying of the air brakes will be accomplished without causing jars or jolts which usually accompany devices of this character.

With the above and other objects in view I now proceed to describe my invention in the following specification and accompanying drawings, in which,

Figure 1 is a view of my improved device as it would appear when operating in connection with a railroad, Fig. 2 is a detail view of the operating mechanism used in connection with my improved train stop, Fig. 3 is a longitudinal sectional view of Fig. 2, Fig. 4 is a detail view of the arrangement of the operating device with relation to the air valve, and Fig. 5 is a detail view of the trip mechanism showing the same in its raised position.

Referring to the drawings by characters of reference 1 indicates the usual railroad track, adjacent which, and extending upwardly from the surface of the ground, is provided the usual signal post 2. This signal post has secured adjacent its upper extremity the semaphore 3 which is pivotally mounted thereon and adapted to be

actuated in the ordinary manner. A suitable chain or flexible connection 4 is secured to the semaphore 3 and passed downwardly and over a wheel 5 which is rotatably mounted on the bracket 6, supported by the post 2. This flexible connection is extended as clearly illustrated at 7 and the end secured to the operating mechanism of the trip device. This trip device preferably comprises the standard 8 which is preferably supported by a base 9. This standard 8 extends upwardly as is clearly illustrated and has pivotally secured thereto a suitable bar 10 having formed integral therewith and at the outer extremity thereof a plate 11 which is preferably semi-circular in plan and provided with a sharpened edge around its periphery. The end of the flexible member 7 is connected to the bar 10 at the end opposite the plate 11, and it will be obvious that when pull is exerted upon the flexible member, said bar will be raised to a horizontal position and with the sharpened edge extending outwardly and in the direction of the track as will be more fully hereinafter described.

Having described the trip mechanism in the foregoing I will now proceed to describe the attachment to the locomotive. The boiler of said locomotive is indicated by the numeral 12 and the cab by the numeral 13, the usual trailing wheel 14 is secured beneath the cab in the ordinary manner and is provided with a means to secure my improved attachment thereto. A suitable angle bar 15 is rigidly secured to the locomotive by any suitable means and extends outwardly therefrom for a short distance. The outer extremity of this bar 15 is provided with a suitable aperture through which a rivet or bolt of lead, copper, or similar soft material is adapted to extend, this rivet being indicated by the numeral 16. Suitably supported intermediate the ends of the bar 15 I preferably provide the plate 17 which is preferably cylindrical in conformation and has formed thereon the ears 18, the use of which will be more fully hereinafter described. A suitable aperture 19 is formed in the center of the plate and is adapted to receive the operating mechanism, and thereby permit the plate to rotate freely with relation to the operating mechanism. A plate 20 similar to the plate 17 is provided with an aperture 21 and is adapted to receive the rivet 16 when the device is in

use. This plate 20 has formed integral with its inner face the ears 22 which are adapted to align with the ears 18 of the plate 17 and thereby support the coil spring 23 in operative relation with the plates, as will be clearly seen upon referring to Fig. 3 of the drawings.

The axle of the wheel 14 of the locomotive is preferably extended as clearly illustrated at 24 and provided at its outer extremity with a suitable plate 25 which is secured to said axle in any suitable manner. A longitudinal key 26 is secured to the axle in any preferred manner and is adapted to extend 15 into a groove 27 formed in the longitudinally extending central bore 28 of the clutch cone 29. This clutch cone is provided around its periphery and adjacent its outer extremity with a circumferential groove 30, 20 which is adapted to receive the tongue formed integral with the plate 20. Intermediate the groove 30 and the inner extremity of the clutch cone I preferably provide the beveled surface 31 which is adapted to cooperate with the arms extending outwardly 25 from the coöperating clutch member.

Rotatably mounted on the axle extension 24 I preferably provide the sleeve 32 having the enlarged portion 33 formed at one end thereof, this enlarged portion being provided with a circumferential groove 34, which is adapted to receive the inner edge of the circular plate 17 as will be clearly seen upon referring to Fig. 3. Formed integral 35 with the enlarged portion 33 and extending outwardly therefrom in the direction opposite the sleeve 32 I preferably provide the arms 35 having their ends upturned as shown at 36 to provide for frictional engagement with the surface 31 of the clutch cone 29. At the end of the sleeve 32 opposite the enlarged portion 33 I preferably provide a suitable sprocket wheel 37 having the teeth 38 formed thereon, the use of 40 which will be more fully hereinafter described.

Extending over the sprocket wheel 37 and coöperating therewith I preferably provide a suitable chain 39 which is operatively connected with a sprocket wheel 40, which in turn is mounted on the shaft 41 which extends transversely of the cab of the engineer and has mounted at its opposite extremity the sprockets 42 and 43, respectively, the 45 sprocket 42 being adapted to coöperate with a similar sprocket 44, through the medium of a chain 45, and thereby drive the shaft 46, which in turn is operatively connected with the engineer's air valve.

60 A chain 47 which extends over the sprocket wheel 43 is provided and is adapted to coöperate with a suitable sprocket 48, this sprocket wheel 48 being secured to a suitable shaft which carries a spur gear 49, this spur 65 gear being adapted to coact with a suitable

rack bar 50 which is supported by the throttle lever 51, as will be clearly seen upon referring to Fig. 4.

The operation of the device will be substantially as follows: When the semaphore 70 of the block signal, indicated by the numeral 3, is in its raised position the plate 11 will extend horizontally and in close proximity to the railroad track. An approaching locomotive carrying my attachment will ordinarily run by a block when the signal is down, but should the semaphore indicate danger my improved attachment will be engaged by the plate and owing to the sharpened edge of said plate the rivet or bolt 16, 80 which is of softer material than that from which the plate is made, will be broken, thus permitting the springs 23 which are under tension to pull the cone into an engagement with the spring arms, thereby causing the 85 arms to rotate with the cone which in turn will operate the sprocket 34 and through the medium of the chains and sprockets, previously described, will shut off the power and apply the air without in any way requiring manual labor.

While in the foregoing I have shown and described the preferred embodiment of my invention, I wish it to be understood that I may change the specific arrangements of 95 parts without in any way departing from the spirit and scope of my invention.

What I claim is:—

1. In combination an automatic train stop including a track trip, a stop mechanism, 100 said stop mechanism comprising an extension formed integral with the axle of one set of wheels of the locomotive, a clutch member revolubly mounted on said extension, a coöperating clutch member slidable 105 on said extension and adapted to revolve therewith, a sprocket connection on the revoluble clutch member, means to connect the sprocket with the control of the locomotive, springs to exert pull on the clutch members 110 to bring the same into engagement, and means to hold the clutch members out of engagement, said means designed to be released upon engagement with the track trip.

2. A train stop including a track trip, a 115 train-carried stop mechanism comprising an extension formed on the axle of one set of wheels, a sleeve rotatable on said extension, a sprocket formed integral with the sleeve, means to control the movement of the locomotive, means connecting the movement-controlling means with the sprocket, the sleeve being provided with an annular groove at the end opposite the sprocket, a stationary support secured to the locomotive, a plate 120 supported on the stationary support, and seated within the annular groove in the sleeve to form a bearing therefor, a pair of arms carried by the sleeve and projecting longitudinally with relation thereto, a clutch 125

130

half slidable longitudinally on the axle extension and designed to rotate therewith, said clutch half being arranged to engage the arms to cause the sleeve to rotate, a plate secured to the clutch half and free to rotate thereon, springs connected to the plate and to the support for the sleeve to normally exert inward pull to hold the arms in engagement with the clutch half, and a rivet of relatively soft material engaging the plate and the stationary support to hold the sleeve

and clutch half in spaced relation, said rivet being designed to be severed to permit the clutch half to engage the arms when the device is operated.

In testimony whereof I affix my signature in presence of two witnesses.
15

DANIEL HOPKINS.
